UNITED STATES PATENT OFFICE.

HENRY MILLHOLLAND, OF READING, PENNSYLVANIA, ASSIGNOR TO THE DARLING PUMP & MANUFACTURING COMPANY, LTD., OF WILLIAMSPORT, PENNSYLVANIA, A LIMITED JOINT STOCK COMPANY ORGANIZED UNDER THE LAWS OF PENNSYLVANIA.

GATE-VALVE.

No. 808,561.

Specification of Letters Patent.

Patented Dec. 26, 1905.

Application filed January 29, 1903. Serial No. 141,007.

To all whom it may concern:

Be it known that I, HENRY MILLHOLLAND, a citizen of the United States, and a resident of Reading, in the county of Berks and State 5 of Pennsylvania, have made certain new and useful Improvements in Gate-Valves, of which the following is a specification.

My invention is an improvement in gate-valves, and particularly in that class of such 10 valves having rotative parallel disks operated by wedges or spreading devices; and the present invention has for objects, among others, to provide a novel construction whereby the main or body wedge-block supports 15 all the movable parts and whereby the thickness of the valve is reduced to a minimum, thus reducing the weight and amount of material necessary for the construction of the valve to the minimum and incidentally reducing to the minimum the weight of the 20 valve-casing by reducing the distance between its opposite valve-seats; and the invention consists in certain novel constructions and combinations of parts, as will be 25 hereinafter described and claimed.

In the drawings, Figure 1 is a vertical longitudinal section of the gate-valve embodying my invention. Fig. 2 is a transverse section thereof, showing a different form of connection between the valve-stem and the valve. 30 Fig. 3 is a detail perspective view of the main or body wedge-block with the bottom wedge-block suspended thereon. Fig. 4 is a detail perspective view of the main or body wedge-block. Fig. 5 is a detail perspective view of the bottom wedge-block. Figs. 6 and 7 are detail perspective views of the opposite disks. Fig. 6^a shows a modified form of trunnion, and Figs. 4^a and 4^b illustrate modified forms 35 of the projections on the main or body wedge-block for supporting the bottom wedge-block.

In carrying out my invention I seek to so construct the several parts as to avoid any unnecessary space between the outer faces of 45 the opposite valve plates or disks, and in doing this I bear in mind the necessity of constructing the studs on the valve plates or disks of sufficient length to properly support the said parts in both the open and closed 50 position of the valves, as well as the fact that the said studs should not project in the closed position of the valve into the central space or

bore A' of the main or body wedge-block A, such space or bore being the clearance-space for the screw B, by which the valve is ordinarily raised or lowered. I also bear in mind the desirability of supporting the disks C so the latter can freely turn and so their rotary motion will not be impeded in any degree by the weight or friction of any separate parts 55 operating thereon.

In the construction shown the valve-casing D may be of ordinary form, having the opposite seats D' and the base-abutment E, upon which the bottom wedge-block bears 65 when the valve is lowered to closed position, as shown in Fig. 1.

The main or body wedge-block A has the longitudinal bore or passage A' and is provided with the bearings a for the studs C' of 70 the disks C, said bearings a being in the nature of openings leading from the opposite sides of the wedge-block A into the central passage or bore A'. On one side the main or body wedge-block A has a projection A² 75 surrounding one of the openings a and designed to support the bottom wedge-block F. The main block A has the inclined or wedge surfaces a' at its opposite sides, which oppose the inclined surface f' of the bottom wedge 80 F, said surfaces f' being at the edges of the side plates f and the front plate F' of the block F being provided with an opening F², which fits over the projection A² of the body A, so the bottom wedge-block will be supported on the projection A² of the section A, 85 as shown in Fig. 3, when the parts are assembled, as shown in Figs. 1 and 2 of the drawings.

When the parts are assembled, it will be 90 noticed the studs C' of the valve-plates project into the bearings a, but do not extend into the clearance-space A' formed in the body or block, and the valve-plates rest flat against the opposite sides of the body-block 95 A and there is no lost space between the opposite outer surfaces of the valve-plates. It will also be noticed that the valve-plates when the valve is raised slightly are free to rotate on their axes, so that new surface of 100 contact may be presented between the gates and their seats, and this rotation of the disks or plates will not be impeded by any frictional bearing of the bottom wedge-block on

the studs of said disks or plates, as the bottom block is supported entirely upon the main or body wedge-block, as will be understood from Fig. 3 of the drawings. It will 5 also be noticed that the movable parts—namely, the opposite valve-plates and the bottom wedge-block—are all supported directly upon the main or body wedge-block A and are moved positively by said body-block 10 in the operation of the parts to open the valve.

It will be noticed that in fitting the studs of the disks or valve-plates to the bearings in the body-block sufficient allowance is made 15 for the release of the bottom wedge-block before the disks are raised, this being secured by loosely fitting the parts together, as will be understood from the drawings.

The studs on the valve-plates may be 20 made cylindrical, as illustrated in Figs. 6 and 7, or may be slightly conical, if desired, as shown at G in Fig. 6^a. It also may be found desirable in some instances to make the projection on the main wedge-block for supporting the bottom wedge-block square, as shown at H in Fig. 4^a, or slightly conical, as shown at I in Fig. 4^b, instead of cylindrical, as shown in Fig. 4.

In operating my gate-valve downward 30 pressure may be exerted upon the valve by means of a screw B, as shown in Fig. 1, or a rod B', as shown in Fig. 2, in the ordinary manner. When this is done, the pressure on the top wedge acting in connection with the 35 lower wedge the latter bearing upon the abutment E in the casing will spread the parallel disks or valve-plates against their seats, thus closing the valve securely, as desired. When it is desired to open the valve, the lifting of 40 the body or main wedge-block releases the valve plates or disks by the upward movement of the body-section A along the wedge surface of the bottom wedge F, after which the further upward movement of the body or 45 wedge block A will lift the valve to open position, as desired.

It will be seen that an important feature of my invention is the supporting of the bottom wedge-block directly upon the main or body 50 wedge-block and the construction whereby such supporting of the bottom wedge-block coöperates in securing the minimum width or distance between the working faces or valve-seats of the disks, thus effecting an economy 55 in the construction of the valves by economizing the amount of material necessary in the construction of the valves and incidentally reducing to the minimum the weight of material in the casing, thus providing valves 60 and operating devices which will embody the maximum strength and efficiency in the minimum space. As before suggested, the supporting of the bottom wedge-block directly upon the main wedge-block and entirely independent of the valve-disks or either of the 65

disks secures a direct operation of the bottom wedge-block by the main wedge-block and avoids any interference by the bottom wedge-block with the rotary movement of the disks or valve-plates.

Having thus described my invention, what I claim as new, and desire to secure by Letters Patent, is—

1. The improvement in gate-valves herein described comprising the main or body wedge-block having a longitudinal bore or passage and provided in two opposite sides with openings forming bearings for the trunnions of the valve-disks and having surrounding one of said openings a projection whereon to support the bottom wedge-block and provided on its two other opposite faces with inclined surfaces, the bottom wedge-block having side plates provided with inclined surfaces coöperating with those of the body wedge-block, and a front plate having an opening receiving the projection on the main wedge-block and fitting over said projection whereby the bottom wedge-block may be supported thereon and directly by the main or body wedge-block, the opposite valve disks or plates provided with inwardly-projecting studs turning in the bearings in the body wedge-block and the casing for said valve, all substantially as described, whereby the bottom wedge-block and the valve plates or disks may be supported directly by the body wedge-block substantially as and for the purposes set forth.

2. The combination in the gate-valve with the body wedge-block of the valve disks or plates supported at the opposite sides thereof, and the bottom block supported directly by the body wedge-block and operating between the same and one of the valve plates or disks substantially as set forth.

3. The combination of the body wedge-block having a longitudinal opening or bore and provided in its opposite sides with openings leading to said bore and forming bearings for the studs of the valve plates or disks, the valve plates or disks arranged on opposite sides of the body wedge-block and having studs projecting into the bearing-openings thereof, and the bottom wedge-block operating between the body wedge-block and one of the valve-plates and supported directly by the body wedge-block substantially as set forth.

4. The combination in a gate-valve of parallel rotative disks, having journal-studs, the main wedge-block having apertures for the reception of said studs and provided around one of said apertures with a support for the bottom wedge-block, and the bottom wedge-block suspended from said support substantially as and for the purpose set forth.

5. The combination in a gate-valve of the valve-plates and the body or main wedge-block having on one side a projection form-

ing a support for the bottom wedge-block, the bottom wedge-block supported on said projection and having an opening receiving the same and the opposite rotative disks substantially as set forth.

5. The combination of the main wedge-block, the opposite rotative disks, connections between the disks and the main wedge-block, and the bottom wedge-block operating between the main block and one of the

disks and supported independently of the connections between the said disks and the body wedge-block whereby the bottom wedge-block is carried by the body independently of the rotative disks.

HENRY MILLHOLLAND.
